UNITED STATES PATENT OFFICE.

HALBERT E. PAYNE, OF NEW YORK, N. Y.

TYPE-WRITING MACHINE.

1,174,438.

Specification of Letters Patent.

Patented Mar. 7, 1916.

Application filed June 14, 1913. Serial No. 773,623.

To all whom it may concern:

Be it known that I, HALBERT E. PAYNE, a citizen of the United States, residing in the city, county, and State of New York, have invented certain new and useful Improvements in Type-Writing Machines, of which the following is a specification.

This invention relates to typewriting machines, and has for its object to provide an exceedingly simple and low-cost mechanism, suitable for use as an educational typewriter and also for the production of commercial work.

To this end the invention comprises the parts, improvements and combinations herein shown and described in its preferred embodiments and more particularly pointed out in the appended claims.

In the accompanying drawings illustrating the invention: Figure 1 is a perspective view of a preferred embodiment of the machine; Fig. 2 is a front view thereof, the index plate being removed; Fig. 3 is a perspective view of a form of letter-space mechanism; Fig. 4 is a vertical sectional view, showing the parts in normal position; Fig. 5 is a similar view, showing the parts in the positions which they assume when the index plate is depressed and the presser foot is in the act of producing an impression; Fig. 6 is a fragmentary plan view showing certain parts beneath the index plate, the latter being removed; Fig. 7 is a vertical sectional view showing a modified construction; and Fig. 8 is a fragmentary plan view of parts with the index plate removed.

The parts are mounted on a suitable flat base, which is shown as comprising a wooden slab 1, on which is mounted a metal plate 2, parts of the latter being struck up to afford bearings for the actuating parts, which, as will become apparent, are few and simple in construction. A suitable impression surface is provided, and, as shown, it is preferably a part of an upstanding, step-by-step, movable letter-space carriage 3. The latter comprises an elongated bottom plate 4, which is slidably guided on the base plate 2 and provided with upwardly-projecting end pieces 5. The latter are connected at their upper portions by an angular member 6, the approximately vertical front face 7 of which constitutes the impression surface. A paper feed roller 8 has

journals revoluble in the standards 5 and is provided at one end with an appropriate knurled hand wheel 9, the roller being limited to line space movement by a spring pawl 10 engaging the notched base 11 of the 60 wheel 9. A sheet metal paper guide 12 is secured to the top of the bottom plate 4 and is curved upwardly and forwardly to coöperate with the forward portion of the feed roller. The paper carriage is guided 65 in its movement by an upstanding flange 13, formed at the rear edge of the base plate 2, and by another flange or lug 14 which overhangs the forward edge of the bottom plate 4. This forward edge of the bottom plate 70 of the carriage is formed as a letter-space rack 15, which coöperates with the actuating parts of the letter-space mechanism herein-after described.

An index plate 16 or 16^a is disposed over the forward portion of the base and bears character designations 17, which are laid out in three or more straight rows, the arrangement of the characters being that of the keyboard of a standard writing machine. From front to rear these characters are in staggered or oblique relation, so that the index, presently to be described, can register with only one character at any position to which it may be shifted laterally. That is to say, from front to back no character is directly in alinement with any other character. The index plate preferably slopes downward and forward and is provided with depending front and end walls, designated 18 and 19 in Fig. 1 and 18^a and 19^a in Fig. 7, so that the whole constitutes a species of hood for inclosing and protecting certain parts. The characters 17 are desirably formed on a sheet or plate 20 or 20^a which underlies the index plate, the latter being provided with circular apertures 21 through which the characters appear, the character-bearing plate being held in position in any suitable manner.

The printing type 22 are formed on a straight, horizontally-elongated, flexible rubber band 23, which is united at one longitudinal edge to the edge of a rigid support in the form of an elongated metal plate 24, the connection between the rubber band and metal plate being preferably effected by vulcanizing. The type carrier thus constituted is mounted for rectilinear movement parallel to the paper carriage and impre- 110

sion surface and crosswise of the machine for the purpose of selectively positioning the type to print, and also for tilting movement transverse to this type-selecting movement for the purpose of effecting the impression.

In the preferred mode of organizing the machine a comparatively narrow space is afforded between the index plate 16 and the paper carriage 3, and the type carrier is disposed upright in this space so as to slide and tilt on bearings at its lower edge. To this end the plate 24 has a cylindrical bearing portion or bead 25 formed on or secured to its lower edge, and this shaft-like portion engages circular bearing openings formed in brackets 26 which rise from the base plate 2. The bearings afforded by these brackets are slotted or notched at the top, as shown at 27, so as to permit the passage of the plate 24, and the rear edges 28 of these notches constitute stops which limit the plate 24 in its rearward movement to a position beyond which the flexible type band 23 must be locally flexed in order that the selected character may reach the printing point, (see Fig. 5). The provision of a definite stop to arrest the rigid support 24 in the same position at each printing operation is of value as it insures good alinement. The forward edges of the notches 27 also constitute stops for limiting the return movement of the type-carrier, which is permitted to move away from the compression surface far enough for visibility.

Means are provided for holding the rigid part of the type-carrier against its positive stop while the presser foot is engaged in locally flexing the type-band to produce the impression. This means is preferably of a yielding character and actuated by the presser foot or impression-producing mechanism, so as to contact with the type-carrier and swing it against the stops 28 prior to the production of the actual impression by the flexing of the band. After the plate 24 has contacted with these stops the said means yields so as to permit the presser foot to complete its movement as shown in Fig. 5. While the particular construction selected may be widely varied, I have illustrated a simple embodiment consisting of a light spring 78 secured to the presser foot and projecting toward the type-carrier, the construction preferably being such that in the printing operation this spring contacts with the carrier before the presser foot engages the flexible portion thereof. During the local flexing of the type-band the spring holds the rigid support 24 against the fixed stop, so that the center about which the type-band is flexed is always the same distance from the impression surface. That is to say, the type-band is flexed about its junction with the rigid plate as a center, and

because the plate is held against a definite stop such center must always have a fixed location during the act of printing. In this way good alinement is insured.

The type 22 are inked by a pad or pads 29, which are secured to the front face of a shield plate 30 apertured at 31 to permit the selected type to be pressed against the paper. The lower portion of the shield plate 30 is curved at 32 so as to engage the cylindrical portion 25 of the type-carrier plate 24 as a pivot bearing, and is confined between the brackets 26 so that it does not partake of the longitudinal movement of the type member.

The pressing of the selected type face against the paper is effected by a fore and aft tiltable presser foot, which is designated 33 in Fig. 4 and 33^a in Fig. 7. This presser foot is operated by the index plate, which is yieldable under finger pressure for this purpose. The drawings illustrate two forms of construction presented in this mode of operation, and the form shown in Figs. 1 to 6 will now be more particularly described. In these views the index plate is fulcrumed so as to tilt up and down about its rear portions, that is to say, the portion nearer the paper carriage. In the construction shown this is accomplished by pivotally connecting the end walls 19 with upward-projecting standards 34, the pivots connecting the parts being designated 35. In the normal position of the index plate the lower edges of the end walls 19 are inclined upward and forward, so that the lower edge of the front wall 18 is disposed at a sufficient distance above the base plate 2 to permit of an adequate downward movement of the index plate. The presser foot 33 is fixed at its lower portion to a rock shaft 36, the ends of which are journaled in the brackets 26 heretofore referred to, and a spring 37, coiled about this shaft and bearing at one end against the brackets 26 and at the other end against the presser foot, serves to restore the latter to normal position shown in Fig. 4. The operating connection between the depressible index plate and the tiltable presser foot consists of a single lever 38, which extends fore and aft beneath the index plate and is fulcrumed intermediate its ends as shown at 39 on a standard 40. The rear end of this lever is formed as a flat tongue 41, which engages a notch 42 in a rearward extension of the presser foot. At its forward end it bears against the index plate or the front wall 18, where it may pass through a notch 43.

The letter-space mechanism includes a member 44, which extends fore and aft beneath the index plate at one side of the presser foot operating lever 38 and is connected at the rear end with the feed pawl 45, while its forward end is arranged to be

actuated by the depression of the index plate. Preferably, its forward portion underlies the front end of the printing mechanism lever 38, so that depression of the forward end of the latter also depresses the underlying portion of the letter-space member. To this end the said member 44 has a lateral extension 46, which is in engagement with the lever 38 as shown. Depression of the lateral extension 46 causes the member 44 to rock about a longitudinal axis and thus retract the pawl 45, which is pivotally connected to a downward-projecting arm 47 at the rear end of the member. A simple and advantageous construction is secured by making the member 44 in the form of a sheet metal bar, which is rockably mounted by engaging it at one edge in notches 48 formed in a standard 49 and a lug 50 bent from one of the brackets 26 heretofore referred to. The member is held from disengagement from these notches by a simple upstanding lug 51 at the opposite edge of the member. The member is held in normal position by a spiral spring 52, which is secured at one end to a lug 53 bent down from the member and at the other end anchored in an opening 53a in the standard 40. This spring also tends to hold the letter-space rocker in engagement with its notched bearings. Upon release of the finger pressure exerted on the index plate at the conclusion of the printing operation, this spring 52 rocks the member 44 so as to elevate the lateral extension 46 and thereby restore the index plate to normal position. In this action it also tends to restore the presser foot 33 and the lever 38 to normal position, though preferably a separate spring 37 is provided for insuring the restoration of these parts, as already described. The same contractile movement of the spring 52 projects the feed pawl 45, which is in engagement with a tooth of the feed rack, so as to advance the carriage 5 the distance of one letter. In so doing the pawl is projected beneath an overhanging stop 54, which locks the pawl to the feed rack and insures the holding of the carriage in position for the impression. This overhanging guard also retains the pawl in operative relation to the feed rack. Gravity may be relied on to cause the end of the feed pawl to drop between the teeth of the rack, or a small spring may be used for the purpose.

The lateral extension 46 is disposed in front of the index plate and affords a flat, transversely-elongated surface, constituting it a suitable letter-space member operable by the finger or thumb independently of the index plate and printing lever 38. Depression of this member also releases the carriage, permitting it to be returned for the starting of another line. Where the member 44 passes beneath the lower edge of the

front wall 18 it is offset downwardly as shown at 55, so as not to obstruct the downward movement of the index plate.

The selecting movement of the flexible type-band is effected by means of an index, 70 which co-operates with the index plate. In the construction shown a wire bail 56 extends across at the rear part of the index plate and has downwardly-bent end members 57, the extremities of which are bent inward and received in sockets afforded by the cylindrical portion 25 of the type-band support 24. Thus, a pivotal engagement is secured between the bail 56 and the member 24, so that on the one hand the bail is not 75 affected by the tilting movement of the type-band support provided for visibility, while on the other hand the bail may be swung without affecting the type-carrier. An arm 58, preferably in the nature of a U-shaped 80 piece of wire, is secured at its rear end to the middle of the bail 56 and extends forward over the index plate. On it is slidably mounted a finger piece or index member 59, which is preferably in the form of a 85 circularly-clipped disk adapted to fit into the circular openings 21. It is provided with lateral eyes 60 which embrace the rods 58, and an elastic band 61, secured at its opposite ends to the sides of the finger piece, 90 serves to hold the finger of the operator against slipping out of place.

In operation the operator inserts the tip of his forefinger in the finger piece 59, and by sliding the latter back and forth on the 100 arm 58 and moving it laterally with the bail 56 he is able to cause it to register with any one of the character designations 17 on the keyboard. The lateral movement of the bail, by virtue of its direct engagement with 105 the type-band support 24, produces similar endwise movement of the type-band, and the positions of the type on the type band and of the characters on the index plate being properly correlated, any character thus 110 selected on the index plate is selectively brought into printing position on the type-band. Since the characters on the index plate are all displaced laterally with reference to each other, a complete set of characters can be arranged in line on the type-band. The formation of the finger piece 59 so that it fits into and registers with the 115 circular character openings 21 insures the exact positioning of the selected type-band character in printing position. In order further to insure this exact positioning and to guard against displacement, a rack 62 may be secured to the front side of the type-band support 24. The teeth of this rack are 120 arranged to receive the shank of the presser foot 33 between them when the presser foot is moved rearward to print; and, the space between the teeth being substantially equal to the width of such portion of the presser 125

foot and the extremities of the teeth being beveled so as to afford flaring entrances to such spaces, the said movement of the presser foot will automatically effect any slight endwise shifting of the type-carrier which may be necessary to locate the selected type in the exact printing position. The operator having in this manner selected the type which is to print, presses downward on the finger piece 59 and thereby depresses it and the index plate. This movement tilts the bail 56 forward and the type-carrier 23, 24 rearward. The tilting of the type-carrier is produced by the pressure of the index plate upon the forward end of the printing lever 38, the rear end of this lever being thereby elevated so as to force the presser foot 33 rearward. When the type-band is first engaged by the presser foot the said band and its rigid support 24 are tilted rearward together, but, the support encountering the stop 28, the further rearward movement of the presser foot locally flexes the type-band about its junction with the support 24 as a center. By providing for the bodily fore and aft tilting of the type carrier the printing is rendered visible, and by establishing a definite position for the support 24 during the printing operation alignment is insured. The depression of the index plate also rocks the letter-space member 44 so as to retract the feed pawl 45 and tension the spring 52. When the operator relaxes the finger pressure on the index plate the parts are restored to normal position and the feed pawl 45 is actuated to advance the paper carriage in the manner already described.

The construction shown in Figs. 7 and 8 is substantially similar to that shown in the other views, but differs in certain features which will now be pointed out. The index plate 16^a is fulcrumed at its forward portion, being connected by pivots 35^a with standards 34^a rising from the base plate 2. Consequently, the lower edges of the end walls 19^a are normally inclined upward and rearward. In this construction the presser foot 33^a is operated directly by a depressible index plate by the engagement of the rear portion of this plate with the upper portion of the presser foot. To this end a roller 70 is suitably mounted on the index plate, so as to roll on a suitably formed forward edge 55 of the presser foot. The presser foot has a forward extension 71, which in this instance is for the purpose of actuating the letter-space mechanism. The latter includes a rock member 44^a which extends fore and aft beneath the index plate, and, as here shown, may be in the form of a cylindrical shaft engaging open bearings in brackets 49^a and 50^a. The said member carries a laterally extending arm 72 which overlies the notched forward end of the presser foot extension

71, so that upward movement of the latter elevates the arm and thus rocks the member 44^a. The rear end of this member is bent downward as shown at 47^a, and the feed pawl 45 is pivotally connected to this portion in substantially the same manner as in the other form of the invention illustrated. A spring 52^a, which is connected at one end to the base plate and at the other end to a downward-projecting arm 53^a, is placed under tension by this movement of the member 44^a, and when the finger pressure is relaxed serves to restore the latter to normal position and thus cause the feed pawl 45 to advance the paper carriage. No special spring is shown for restoring the presser foot to normal position, and accordingly this construction illustrates the fact that the same spring which restores the letter-space member may also restore the presser foot. While this same spring effort transmitted through the presser foot to the index plate might be utilized to restore the latter also to normal position, a special spring may be utilized for this purpose, as indicated at 73. The rocker 44^a projects at the front through the index plate and is provided with a laterally-extending space bar portion 46^a, which, like the space bar portion 46 of the other construction, is depressed by the operator to effect spacing between words and release of the carriage. A post 74 rising from the base serves to limit the downward movement of the index plate. The upward movement of the latter may be limited, both in this and in the other construction, by brackets 75, which overhang lugs 76 bent inward from the lower edges of the end walls 19 or 19^a. The type carrier 23, 24 and also the shield 30 may be restored to normal position, that is to say, moved forward away from the impression surface after each impression, by means of a light spring 77, which in figure is shown fastened to the rear side of the shield and bearing at its other end against one of the brackets 26.

What I claim as new is:

1. In a typewriter, the combination of a base, an upstanding paper carriage mounted for letter space movement on the back portion of the base, an index plate fulcrumed on the base in front of said paper carriage, a horizontally elongated flexible type-band, means supporting the same upright between said index plate and paper carriage for longitudinal type-selecting movement parallel to the latter, an index connected to said type-band and extending forward over said index plate, a tiltable presser foot in front of said type-band, and means whereby the index plate operates the presser foot.

2. In a typewriter, the combination of an impression surface, a movable index plate having a plurality of rows of characters

- thereon, a horizontally elongated, flexible type-band mounted upright between the impression surface and index plate and movable lengthwise to select the desired type, a bodily movable index connected with the type-band and coöperating with said index plate, and means actuated by the movable index plate for impressing the selected character on the band against the impression surface.
6. In a typewriter, the combination of an impression surface mounted for letter space movement on the base, a movable index plate mounted to rock in standards uprising from the base, a horizontally elongated flexible type-band, a longitudinally slidable and transversely tilttable rigid support to which said type-band is fixed, an index connected to said support and coöperating with the index plate, and a presser actuated by the index plate to engage the selected portion of the type-band.
7. In a typewriter, the combination of an impression surface mounted for letter space movement on the base, a movable index plate mounted to rock in standards uprising from the base, a horizontally elongated flexible type-band, a longitudinally slidable and transversely tilttable rigid support to which said type-band is fixed, bearings in which said support is slidable and tilttable, an index movably connected to said support and coöperating with the index plate, and a presser actuated by said movable index plate to tilt said support and locally flex the type-band to produce an impression.
8. In a typewriter, the combination of an impression surface, a rocking index plate mounted to rock in standards uprising from the base, a horizontally elongated flexible type-band mounted vertically between said impression surface and said index plate, means supporting the same vertically between the index plate and impression surface for longitudinal and bodily tilting movements, an index pivoted to the type-band and coöperating with the index plate to move the band longitudinally, and a presser actuated by the index plate for locally flexing the band to produce the impression.
9. In a typewriter, the combination of a base, an impression surface on the rear portion thereof, a depressible index plate fulcrumed on the support in front of the impression surface, a horizontally elongated flexible type-band mounted upright between the impression surface and index plate, an index connected with the type-band to move the same longitudinally to select the desired type, a presser, and means whereby depression of the index plate forces said presser rearward against the selected portion of the type-band.
10. In a typewriter, the combination of a base, an impression surface on the rear portion thereof, a depressible index plate fulcrumed on the support in front of the impression surface, a horizontally elongated flexible type-band mounted upright between the impression surface and index plate, an index connected with the type-band to move the same longitudinally to select the desired type, an upstanding presser foot pivoted on the base in front of said type-band, means whereby depression of the index plate rocks said presser foot rearward, and means for restoring the index plate and presser foot to normal positions.
11. In a typewriter, the combination of an impression surface, a pivotally mounted depressible index plate, a horizontally-elongated lengthwise-movable flexible type-band, an index connected therewith and coöperating with the index plate, a tilttable presser foot for engagement with the selected portion of the band, and a lever constituting an operating connection between said index plate and presser foot.
12. In a typewriter, the combination of an impression surface, an index plate in front of said impression surface, said index plate being pivotally supported at the back so as to be depressible, a spring normally sustaining said plate, a horizontally-elongated flexible type-band, an index connected therewith for moving the same lengthwise to select the desired type, a presser foot arranged to engage with the selected portion of the type-band, and a lever engaged by the forward part of the index plate and connected with said presser foot.
13. In a typewriter, the combination of a base, a step-by-step movable paper carriage mounted on the rear portion thereof, a depressible index plate fulcrumed at its rear portion on the base in front of said paper carriage, a longitudinally-movable flexible type-band located between said index plate and paper carriage, an index connected with said band and coöperating with the index plate, a presser foot pivotally mounted in front of said type-band to vibrate backward and forward, and a lever extending fore and aft beneath the index plate and engaged at the forward end thereby and at the back connected with said presser foot.
14. In a typewriter, the combination with an impression surface, an elongated type carrier bearing printing characters arranged in line and being shifttable endwise to selectively position its type, and a member adapted to press the selected character against the paper, of a depressible index plate, a printing lever fulcrumed intermediate its ends and extending fore and aft beneath the index plate so as to be pressed thereby to actuate the impression-producing member, and a letter-space member likewise extending fore and aft beneath the index

- plate and having a portion engaging the printing lever so as to be actuated therewith on depression of the index plate and also independently operable.
5. 12. In a typewriter, the combination of an impression surface, an elongated type carrier bearing printing characters arranged in line and being shiftable endwise to selectively position its type, a depressible index plate, an impression-producing member actuated by said index plate, and letter-space mechanism including a space bar projecting in front of the index plate and having a portion underlying said impression-producing member so as to be actuated either thereby or independently thereof.
10. 13. In a typewriter, the combination of an impression surface, an elongated type carrier bearing printing characters arranged in line and being shiftable endwise to selectively position its type, a depressible index plate, an impression-producing member actuated by said plate, a rocker extending fore and aft beneath the index plate, being 15 rockable about a longitudinal axis and having a laterally-extending space bar portion disposed in front of the index plate, a feed pawl connected to the rear end of said rocker and a feed rack with which said pawl 20 co-operates.
25. 14. In a typewriter, the combination with an elongated impression surface and an elongated endwise shiftable type carrier, of an index plate having openings provided 30 with character designations, and a finger piece connected with said type carrier to shift the same and adapted to fit said openings.
35. 15. In a typewriter the combination with an impression surface and an elongated type carrier, of an index plate having character-bearing depressions arranged in a plurality of rows, a frame connected to the ends of said type carrier and having an arm projecting over the index plate, and a cupped finger piece mounted slidably on said arm and adapted to fit said depressions.
40. 16. In a typewriter, the combination with an impression surface, of a type carrier comprising a flexible type-band and a rigid support to which the type-band is secured, said support being mounted to tilt toward 45 and from the impression surface, impres-
- sion-producing mechanism for bodily tilting the type carrier and thereafter locally flexing the type-band, and a fixed stop positioned to be contacted by said support on the printing stroke and to arrest the same in a definite position while the band is locally flexed.
55. 17. In a typewriter, the combination with an impression surface, of a flexible type-band, a support therefor mounted to tilt toward and from the impression surface, a presser foot, and means for holding the 60 tiltable support in a definite position while the presser foot locally flexes the type-band to press the selected type against the impression surface.
65. 18. In a typewriter, the combination with an impression surface, of a flexible type-band, a support therefor mounted to tilt toward and from the impression surface, impression-producing mechanism, a definite stop, and yielding means actuated by the 70 impression mechanism for moving said tiltable support against said stop and there holding it during the local flexing of the type-band to effect the impression.
75. 19. In a typewriter, the combination with an impression surface, of a flexible type-band, a tiltable support therefor, a presser foot, a stop, and a yielding device on the presser foot adapted to hold the tiltable support against said stop during the act of producing an impression.
80. 20. In a typewriter, the combination with an impression surface, of a type carrier comprising a rigid portion mounted so as to be movable rectilinearly for type selection and 85 also tiltable toward and from the impression surface, and a flexible portion mounted on the rigid portion and bearing the type, impression-producing mechanism, a stop, and yielding means actuated by the impression-producing mechanism for holding said rigid portion against said stop during the 90 act of printing.
95. In testimony whereof, I have signed my name to this specification, in the presence of two subscribing witnesses.
